UNITED STATES PATENT OFFICE.

FREDERICK RITZ, OF NAPOLEON, OHIO, ASSIGNOR TO THE HELLER-ALLER COMPANY,
OF NAPOLEON, OHIO, A CORPORATION OF OHIO.

OILING SYSTEM FOR WINDMILLS.

Application filed July 28, 1923. Serial No. 654,418.

To all whom it may concern:

Be it known that I, FREDERICK RITZ, a citizen of the United States, residing at Napoleon, in the county of Henry and State 5 of Ohio, have invented certain new and useful Improvements in Oiling Systems for Windmills; and I do hereby declare the following to be a full, clear, and exact description of the invention, such as will enable 10 others skilled in the art to which it appertains to make and use the same.

This invention relates to improvements in oiling system for windmills or wind-motors, and more especially to a self contained construction which will positively lubricate the 15 movable parts of the motor.

The various features of novelty and invention will appear from the detailed description taken in connection with the accompanying drawings forming part of this 20 specification, and will be particularly set forth in the appended claims.

Fig. 1 is a side elevation partly in section of my improved motor for windmills showing 25 one form of motor to which the invention is applied.

Fig. 2 is a side elevation partly in section of a different form of motor for windmills provided with my improved lubrication 30 system.

Fig. 3 is a plan view of the motor illustrated in Fig. 1 of the drawings, and

Fig. 4 is a plan view of the motor illustrated in Fig. 2 of the drawing.

Like characters of reference are used 35 throughout the following specification and the accompanying drawings to designate corresponding parts.

In both forms of motor there is provided 40 a tubular hub 1 adapted to be supported over the top of a tubular mast (not shown). Supported on the hub is an encasement or bowl 5 adapted to hold oil and support the working parts of the motor. At one side 45 of the hub 1 is a laterally extending hollow arm 2 within which is mounted a pair of pulleys 4 over which is trained a cable or chain 3 leading into the hub 1 from a vane (not shown) which is mounted on the encasement in any suitable manner, it being understood that the vane may be swung by means of the cable 3 by an attendant at the foot of the mast for bringing the vane into proper position when it is desired that the 50 motor shall operate.

Rising from the bottom of the bowl or encasement 5 is an upright tubular member 6 through which passes the pump rod 7. The top of the pump rod has a head 20 which is connected to operating mechanism 60 now to be described. The head 20 of the pump rod supports a shaft 19 on which is pivoted a rocker arm 18 which is mounted at its other end on a shaft 16 supported at the top of a standard 17 which is suitably 65 mounted within the bowl 5. It will now be seen that when the arm 18 is rocked the pump rod will be reciprocated.

For bracing the standard 17 there is provided a brace 15 extending from the shaft 70 16 at the top of said standard to a suitable anchorage point in the bowl as at 15'.

In the form of motor shown in Figs. 1 and 3, the arm 18 is given a rocking motion by the following mechanism. Extending 75 across the bowl 5 and mounted in suitable bearings 9 in the sides thereof is a shaft 8 to one end of which is secured the windmill wheel (not shown). Affixed on the shaft is an eccentric 11 surrounded by an eccentric 80 strap 11' which has an arm 12 extending therefrom. Said arm 12 is pivotally connected to the rocker arm 18 as by a wrist pin 23 extending across an opening in said rocker arm. It will now be seen that as the 85 shaft 8 is rotated by the mill wheel the pump rod 7 will be given reciprocatory movement.

The mechanism for oiling the various parts of the motor will now be described. 90 The bowl 5 is adapted to be filled with oil to a suitable level which will be below the top of the tubular member 6 through which the pump rod extends. Affixed on the shaft 8 is a gear 10 the lower part of which will 95 always be submerged in the oil in the bowl. In mesh with gear 10 is a gear 13 mounted on a shaft 14 extending from the brace 15. Some of the oil carried up by the gear 10 will be taken up by the gear 13 and means are provided to utilize this oil so received on the gear 13 for lubricating the parts.

Disposed over and resting on the gear 13 is the free end of a wiper or lever 24 which is pivoted on the shaft 16 at the top of a standard 17. Projecting from the wiper at an angle thereto is a finger 25 which overlies the adjacent end of the rocker arm 18 which is provided with channels 21 in its upper 100 surface for the purpose of conducting oil 110

received thereon from the finger 25 to the various pivots of the rocker arm. As oil is carried up by the gear 13 some of it will be wiped off by the wiper and run down the 5 rearwardly inclined finger 25 projecting therefrom and be received in the channels in the rocker arm. The bearings of the rocker arm on the shaft 16 receive oil from the channels therein through oil holes 22' 10 in the hub of the arm; the pump rod connection through lateral ways 22 leading from the channels 21; and the wrist pin bearing by similar lateral ways 22.

As the oil is received in the channels in the 15 rocker arm it will flow one way or the other depending on the inclination of the arm as will be readily understood.

The shaft bearings 9 will be suitably lubricated by oil splashed up by the eccentric 20 and also by oil carried up by the gear 10.

In the form of motor shown in Figs. 2 and 4 the wind wheel (not shown) is affixed to a shaft 30 extending through the oil bowl 5 and mounted in suitable bearing 31 in the 25 side walls of the bowl. Affixed on the shaft 30 is a pair of gears 32 adapted to mesh with larger gears 29 affixed on a shaft 28 which is supported between said gears 29 in a bearing 27 which may extend from the 30 tubular port 6, the bearing being preferably braced by a member 26 leading to the end walls of the bowl.

The gears 29 are provided with alined crank pins 38 on their outer faces. Pitmans 35 37 connect the crank pins with the shaft 19 at the top of the pump rod, the shaft being sufficiently long to permit the pitmen to be mounted over the ends of the shaft.

40 The oiling system includes meshed gears 45 and 46, the latter being in mesh with one of the crank pin gears 29.

The gears 45 and 46 are supported on a bracket 42 secured to the brace 15, a shaft 45 43 being provided for gear 45 and a shaft 44' for gear 46.

Gear 45 is wiped by the wiper 24 as already explained. Oil is taken up by gear 45 from gear 46 which takes it up from gear 50 29 as will now be readily understood. The oil on gear 45 is wiped off by the wiper and directed by the finger 25 laterally of the wiper to the channel 21 in the rocker arm from whence the oil is directed to the bearings at either end of the said arm.

55 The pump rod head has an oil deflecting circular flange 20' below the rocker arm

pivot to prevent oil from the pivot from passing through the tubular port 6.

It will be noted that the rocker arm 18 is of slightly different outline in the two motors. In the form shown in Fig. 3 the arm is offset from the intermediate wrist pin connection with the eccentric arm 12 to the pump rod pivot and the connection of 65 said arm with the shaft 16 on standard 17 comprises a pair of hubs at the ends of a fork. In Fig. 4 the arm has a single hub through which the shaft 16 passes and the standard 17 is provided with spaced bearing 70 instead.

Having thus described my invention what I claim as new and desire to secure by Letters Patent of the United States is:

1. In a windmill, the combination with a 75 supporting frame including an oil bowl, of a member pivotally supported at one end and having connection with a pump rod at its other end, means including mechanical mechanisms adapted to convey lubricant 80 from the oil bowl to the pivot joints of said member for lubricating the same, said means including a gear and a pivoted wiper continually resting on said gear, said wiper having means for conducting oil to the top of 85 said member.

2. In a windmill, the combination with a supporting frame including an oil bowl, of a member pivotally supported at one end and having connection with a pump rod at 90 its other end, a gear adapted to receive oil from the oil bowl, a wiper continually resting on said gear, a lateral finger on said wiper overlying said member, the latter having an oil channel into which the oil 95 wiped off said gear by said wiper is received from said finger, said channel leading to the pivot joints of the said member.

3. In a windmill, the combination with a supporting frame having an oil bowl, of a 100 rocker arm pivotally supported at one end and pivotally connected to a pump rod at the other end, means adapted to convey lubricant from said bowl to a level above said arm, said means including a gear, a wiper 105 pivotally supported at one end and having its other end supported on said gear, and means for conducting oil from said wiper to said arm, the latter having means for conducting the received oil to its pivotal bearings. 110

In testimony whereof I affix my signature.

FREDERICK RITZ.
